UNITED STATES PATENT OFFICE.

ENRIQUE VINCKE, OF BARCELONA, SPAIN, ASSIGNOR TO MANUFACTURAS DE CORCHO,
S. A., OF BARCELONA, SPAIN.

COMPOSITE CORK DISK.

Application filed February 8, 1923. Serial No. 617,881.

This invention relates to composite cork disks.

Heretofore it has been proposed to form cork disks for crown caps of two disks, one disk of good quality and another disk of lower quality. However, pursuant to such procedure the cork disks in the regular crown cap assembling machine are charged indiscriminately into a hopper and fed from the 10 hopper to the metal crowns passing through the assembling machine; the chances of the disk of poor quality being positioned in the cap to be outwardly of the disk of good quality are equally as favorable as for the 15 disk for good quality and consequently such proposal is commercially impracticable.

Any attempt, pursuant to the aforesaid procedure, to have the disk of good quality be positioned exteriorly in the assembly of 20 the crown cap, would necessarily include additional operation, attendant with additional expense.

In such prior composite cork disks the disks are secured to one another by resin 25 paper applied on the whole of the contiguous surfaces of the disks and for the reason that substantially all natural cork disks are porous to more or less extent, the resin adhesive is located in contact with the beverage or other liquid of the bottle on which the 30 crown cap has been applied.

Such aforesaid prior and similar proposals have been encouraged by reason of the accumulation of disks of cork bark of poor 35 quality, resulting in the manufacture of disks of high quality.

Generally speaking, in the present day manufacture of disks of natural cork bark, notwithstanding the selection of cork bark 40 to derive the maximum yield of disks of high grade, the proportion of disks of poor quality is from forty to sixty per centum. The disks of poor quality are considered as waste and are disposed of by grinding into granular or powdered form, as for the manufacture 45 of so-called composition cork, for heat insulating purposes and for the manufacture of baked compressed board, the financial return of which is relatively low and emburdened the cost of the disks of good quality 50 to compensate for the losses.

Pursuant to the present invention, and with the aforesaid object of utilizing the disks of poor quality resulting in the manufacture 55 of cork disks of high quality, the

disk is formed compositely of three disks, laid one on top of the other, the two outer disks being of good quality and the inner or central disk of lower quality.

A further feature of the invention resides in applying the adhesive or other binding medium only on such portions of the disks which are located out of the region of possible contact with the beverage or other liquid contained in the bottle, as by applying the adhesive substantially circularly immediately adjacent the edges or the peripheries of the disks, whereby the beverage or other liquid of the bottle is in engagement only with natural cork bark and does not contact with 60 the binding material.

Pursuant to the more preferred forms of my invention, the outer disks are of substantially equal thickness and approximately 65 one-half of the thickness of the inner disk 70 of poor quality.

Further features and objects of the invention will be more fully set forth in the following description and the accompanying 75 drawings, in which—

Fig. 1 shows in elevation the neck and mouth of a crown bottle and in central vertical section a crown cap embodying my invention;

Fig. 2 is a detail perspective view broken 80 away to show the composite disks and one means of securing the same to one another;

Fig. 3 is a detail top plan view of the inner disk and showing the region of application 85 of an adhesive, pursuant to Figs. 1 and 2;

Fig. 4 is a detail perspective view similar 90 to Fig. 2, but showing a modified form for securing the disks to one another.

Referring to Fig. 2 of the drawings, the 95 oppositely disposed, outer disks 10, 11 are of natural cork bark of good quality and the inner disk 12 is of lower quality. As indicated, the thickness of the outer disk 10 is substantially that of the outer disk 11 and the thickness of the inner disk 12 is substantially twice that of each of the disks 10, 11.

The combined thickness of the composite 100 disk formed of the three disks 10, 11, 12 is 105 that of disks accepted in the manufacture of crown caps.

The respective disks 10, 11, 12 may be 110 assembled as a composite disk by means of adhesive applied to the contiguous faces; but the location of application of the ad-

hesive is preferably restricted to the region immediately adjacent the periphery of the disks and disposed outside of the region of possible contact with the contents of the bottle to which the crown cap is applied. Thus, as is indicated in Fig. 3, the central or inner disk 12 is supplied with adhesive 13 within the region indicated between the periphery 14 of the disk 12 and extending inwardly 10 to the substantially circular line 15.

The adhesive is applied to the opposite face of the inner disk 12 in a similar manner and at a similar location as is indicated at 16, see Fig. 2, or an equivalent procedure 15 may be pursued by applying the layer 13 of adhesive on the inner face of the outer disk 10 within a similar region and the other layer 16 of adhesive applied to the inner face of the opposite outer disk 11 within a similar 20 region.

In the assembly of the crown cap, such composite disks are charged into the hopper in bulk, that is to say, indiscriminately, and the provision of cork bark of good quality 25 on the opposite faces of the disk, ensures the locating of the composite disk within the metal shell to have an exposed facing of cork bark of good quality.

As is indicated in Fig. 1, the outer disk 30 10 is shown to be positioned exposedly within the metal crown 17, in which circumstance the opposite disk 11 is brought into engagement with and secured by the usual adhesive to the inner face of the metal shell 17. In 35 the resin collet method of assembling, such opposite disk 11 is brought into engagement with one face of the paper collet, as will be understood. As will appear from Fig. 1, the regions of location of the layers 13, 16 of 40 adhesive for bonding the disks of the composite disk to one another are disposed circularly laterally of the substantially circular region denoted by the indication lines 18, 18, that is to say, circularly outwardly 45 of the region of engagement of the exposed disk 10 with the lip 19 of the mouth of the bottle 20.

The assembly of the three disks may be effected by other procedure, thus as indicated 50 in Fig. 4, the opposite outer disks 10, 11 of good quality and the inner disk 12 of lower quality are bonded to one another by means of the peripherally extending paper 55 21 having adhesive on its inner surface to bond the respective disks 10, 11, 12 circumferentially to one another.

Other forms of uniting the disks 10, 11, 60 12 to one another may be employed, such as by sewing the disks by fine thread, wire stitchings, wire staples, rivets of yieldable material, such as cotton twistings covered

with wax or like material. Preferably, such binding means are applied at two, three or like number of spaced locations and disposed within a region located outwardly of 65 the region of engagement of the cork disk with the contents of the bottle, whereby upon crowning the bottle with the crown cap, the binding medium is located without the region of contact of the beverage or other 70 liquid contained in the bottle.

In a similar manner, composite disks 75 may be formed of more than three disks, the outermost disks being of good quality.

In lieu of employing a disk of lower quality, it may be advisable under certain circumstances to granulate the disks of lower quality and to form therefrom disks of composition cork, and substitute such disks of composition cork for the disk of lower 80 quality in the composite disk.

Whereas I have described my invention by reference to specific forms thereof, it 85 will be understood that many changes and modifications may be made without departing from the spirit of the invention, as defined by the appended claims.

I claim:

1. As a new article of manufacture, a composite cork disk for a crown cap comprising 90 outer disks of natural cork of high quality secured to a cork disk of poor quality and means for bonding said disks to one another disposed circularly outwardly of the region of engagement of said outer disk with the 95 contents of the bottle to which the crown cap is applied.

2. As a new article of manufacture, a composite disk for a crown cap, comprising outer 100 disks of cork of high quality, a cork disk of lower quality and means for securing said disks to one another comprising bonding means located closely adjacent the edges of said disks.

3. As a new article of manufacture, a composite disk for a crown cap, comprising outer 105 disks of cork of high quality, a cork disk of lower quality and means for securing said disks to one another comprising bonding means applied at the edges of said disks.

4. As a new article of manufacture, a composite disk formed of outer disks of cork of high quality, an inner disk of cork of a lower quality united to one another and means for bonding said disks to one another disposed circularly outwardly of the region of engagement of said outer disk with the 110 contents of the bottle to which the crown cap is applied.

In testimony whereof I have signed this 120 specification this 27th day of January, 1923.
ENRIQUE VINCKE.
